(57) **CLAIM**

The ornamental design for purple coated barbed wire fencing, as shown and described.

DESCRIPTION

FIG. 1 is a perspective view of purple coated barbed wire fencing installed on a fence post;

FIG. 2 is a perspective view of a section of purple coated barbed wire fencing;

FIG. 3 is a front elevation view of a section of the fence and a barb secured thereon;

FIG. 4 is a side elevation view thereof; and,

FIG. 5 is a plan view thereof.

A purple coated barbed wire fencing installed between fence posts.

The broken lines are for illustrative purposes only and form no part of the claimed design.
